UNITED STATES PATENT OFFICE.

FRANCIS E. FREY, OF SPRINGFIELD, OHIO, ASSIGNOR OF ONE-HALF TO
LUKE CARLOS, OF SAME PLACE.

LAMP ATTACHMENT FOR SEWING-MACHINES.

SPECIFICATION forming part of Letters Patent No. 251,863, dated January 3, 1882.

Application filed September 3, 1881. (No model.)

To all whom it may concern:

Be it known that I, FRANCIS E. FREY, a citizen of the United States, residing at Springfield, in the county of Clarke and State of Ohio, have invented certain new and useful Improvements in Lamp Attachments for Sewing-Machines; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

The invention relates to a device for swinging a lamp from the head or face-plate of a sewing-machine.

The invention as applied will be understood as set forth in the following specification and claim.

In the accompanying drawings, Figure 1 is an elevation of the device applied to the head of the sewing-machine. Fig. 2 is a top view of the clamp.

Similar letters of reference indicate corresponding parts in all the figures.

A is the lamp; A', the reflector attached thereto. a is a projection under the base of the lamp, which is provided with a socket, a', and is affixed to the exterior of the lamp's bottom, so that the bottom of the lamp is not perforated, and any lamp having a flat metallic bottom can have this socket attached to it.

B is the head or top of the face-plate of a sewing-machine, in which the needle-bar and presser-bar work.

C is the clamp which surrounds the head B. This clamp is closed on three sides and partially open on the fourth. At the back of the clamp a set-screw, c, is let through it, and is tightened up or loosened to secure or release the clamp from whatever it is attached to. The clamp is thus made to surround all of three sides of the sewing-machine head and a part of the fourth side on either corner, and it is consequently secure against coming off by the shake and jar of the machine, while if it only surrounded three of the sides or was clamped upon two opposite sides the jar of the machine

would shake it off. One corner of the clamp is provided with the lug or extension c', provided with a hole or socket, c''. By reason of the projection of the socket outside of the lines of the clamp the bracket and its lamp may be

swung at right angles either to the face-plate 55 or parallel therewith.

D is the swinging bracket, which is supported by the clamp C, and in turn supports lamp. This bracket is formed of a single piece of round metal, as shown, with a spindle, d, 60 for insertion into the socket c' in the clamp C. From the spindle the bracket curves over and has a downwardly extending portion, D', of suitable length, according to the height of the object it is placed upon. A horizontal 65 portion, D'', and a spindle, d'', are turned up from the end thereof and adapted to fit into the socket under the lamp. Both of the spindles d and d'' and the other intervening portions of the arm are formed from a single piece of round 70 metal bent as described.

In use the clamp is fastened to the head of the machine, and the bracket D is placed in the socket of the clamp with the point of the spindle d pointing downward. The lamp is 75 placed upon the spindle d'. The bracket turns freely in any direction in the clamp, and the lamp can thus be placed in any desired position. The lamp also turns freely on the spindle d', and can be turned to throw its direct 80 and reflected light to any desired point. The reflector A' is permanently attached to the lamp, and it turns with it, so as always to be in position to throw the reflected rays directly in line with the direct rays when illuminating 85 any given point or part.

The reflector A' is provided with a hole, o, at the top, by which the lamp can be hung up when not in use. When the lamp is removed the bracket can be used as a cord-reel for a 90 cording attachment on the sewing-machine.

Having thus described my invention, I desire to claim—

The clamp for sewing-machine heads having all of its sides rigid, and provided with a set-screw for tightening it upon the head, and with the lug c', having the socket c'' projecting outside of the lines of the clamp, in combination with the bracket-arm D, having the spindles d d', and with the lamp A a a', substantially as set 95 forth.

In testimony whereof I affix my signature in presence of two witnesses.

FRANCIS E. FREY.
